UNITED STATES PATENT OFFICE.

MERRILL A. FURBUSH, OF PHILADELPHIA, PENNSYLVANIA.

IMPROVEMENT IN LOOMS.

Specification forming part of Letters Patent No. 40,683, dated November 24, 1863.

To all whom it may concern.

Be it known that I, MERRILL A. FURBUSH, of Philadelphia, Pennsylvania, have invented certain Improvements in Looms for Weaving Plain and Figured Fabrics; and I do hereby declare the following to be a full, clear, and exact description of the same, reference being had to the accompanying drawings, and to the letters of reference marked thereon.

My invention relates to that class of fancy looms in which an endless roller chain is used for determining what warp-threads shall be lifted and depressed by means of reciprocating-bars, in combination with hook-jacks and levers connected with the heddles; and my invention consists in certain mechanism, constructed and arranged as described herein-after, for the purpose of operating the heddle-levers and with the view of simplifying the complex machinery heretofore used for the same purpose.

In order that my invention may be understood by those familiar with this class of machinery, I will now proceed to describe its construction and operation.

On reference to the accompanying drawings, which form a part of this specification, Figure 1 is a side view of sufficient of a loom to illustrate my improvement; Fig. 2, a view of Fig. 1, looking in the direction of the arrow; and Fig. 3, an enlarged sectional view of Fig. 1 on the line 1 2.

Similar letters refer to similar parts throughout the several views.

A represents one of the side frames of a loom, and to this frame are secured the two guide pieces B and B', to which are adapted the sliding frames D and D', a vertical reciprocating motion being imparted to the frame D from the crank-shaft B'' through the medium of a rod, E², the upper end of the rod being connected to a pin on the frame and the lower end to a pin, which can be adjusted on the crank-wheel E.

On the outside of the guide-frame B is a stud-pin, a, to which is hung the lever F, and adjustable stud-pin b b', projecting from one arm of this lever into the space between the lugs i i on the sliding frame D, while a similar stud-pin, b', projects from the other arm of the lever into the space between the lugs j j on the sliding frame D', so that the two frames must of

necessity reciprocate in contrary directions to each other.

To the sliding frame D a cross-bar, K, is so secured as to be readily adjusted thereon vertically a similar adjustable cross-bar, K', being secured to the rear of the sliding frame D'.

G G are the usual upper heddle-levers, hung to a pin on the frame; and G' G' are the usual lower heddle-levers, one arm of each upper lever being connected to one arm of one of the lower levers by the ordinary heddle and its strings, and the other arm of the same upper lever being connected to the corresponding arm of the lower lever by a rod, or, as it is termed, a "hooked jack," H, and wire h.

It will be seen on reference to Fig. 3 that the outer ends of the levers G G are situated between the under side of the upper bar, d, of the frame D and the top of the upper bar, d', of the frame D'. It will also be seen that two shoulders, m and n, are formed one on one edge and the other on the opposite edge of each hook-jack, the shoulder m to be struck by the cross-bar K of the frame D during the upward movement of the latter, and the shoulder n to be struck by the cross-bar K' of the frame D' during the descent of the latter as may be determined by the rollers on the endless chain I. As this chain of rollers has been in common use for years, and as its construction and operation on the hook-jacks H are thoroughly understood by those familiar with looms of this class, an elaborate description will be unnecessary. It will also be understood that the under side of the cross-bar d of the frame D serves during the downward movement of the frame to depress to a given position such of the levers G as have been raised by the cross-bar K, and that the upper end of the frame D' serves to elevate to a given position such of the levers G as have been depressed by the cross-bar K'.

I am aware that the end accomplished by the above-described parts has been heretofore attained—as, for instance, in the loom for which Letters Patent were granted to Wm. Crompton, November 25, 1837, and in the looms for which patents were granted to G. Crompton, November 14, 1854, and April 27, 1858, in which patents, however, the mechanism for operating the heddles is of a more elaborate and costly character than that

which constitutes my improvements. I therefore wish it to be understood that I do not desire to claim, broadly, any of the parts above described as performing new functions, but that I limit my claim to the peculiar manner of constructing and arranging the machinery—that is to say, I claim as my invention and desire to secure by Letters Patent—

1. The reciprocating frame D, with its cross-bar K, and the reciprocating frame D', with its cross-bar K', both being arranged to slide in the guide-pieces B and B', or their equivalents, and to operate in conjunction with the

hook-jacks H and other appliances herein described, substantially as and for the purpose set forth.

2. The two-armed lever F, with its projecting stud-pins b and b', adapted to the sliding frames, substantially as specified.

In testimony whereof I have signed my name to this specification in the presence of two subscribing witnesses.

MERRILL A. FURBUSH.
